UNITED STATES PATENT OFFICE.

CHARLES W. LIVERMORE, OF PROVIDENCE, RHODE ISLAND.

DESIGN FOR A PENCIL-CASE.

SPECIFICATION forming part of Design No. 13,519, dated January 9, 1883.

Application filed March 25, 1882. Term of patent 14 years.

To all whom it may concern:

Be it known that I, CHARLES W. LIVERMORE, of the city and county of Providence, and State of Rhode Island, have invented and produced a new and original Design for Pencil-Cases, of which the following is a specification, reference being had to the accompanying drawing, forming part hereof.

My new design is illustrated in the drawing; and it consists of a cylindrical body or barrel, A, with a shorter upper portion, B, also cylindrical, but of less diameter. At the extreme lower or forward end of the case is a short cylindrical portion, D, of less diameter than the barrel, and between the cylindrical portion D and the lower end of the barrel A. The surface is made up of several equal plane faces

C, each raised slightly above the surface of the portion D, but less elevated than the surface of the barrel A, said faces together forming a ²⁰ hexagonal or octagonal or other regular figure of equal sides.

I claim—

The design for a pencil-case herein shown and described, the same consisting of the barrel A, the upper cylindrical extension, B, of less diameter than the barrel, the lower portion made up of plane faces C, and terminating in the cylindrical portion D, all substantially as described, and illustrated in the drawing.

CHARLES W. LIVERMORE.
